UNITED STATES PATENT OFFICE.

JOHN V. RITTMANIC, OF BRADLEY, ILLINOIS.

LOCK.

1,250,019.

Specification of Letters Patent.

Patented Dec. 11, 1917.

Application filed June 11, 1917. Serial No. 174,084.

To all whom it may concern:

Be it known that I, JOHN V. RITTMANIC, a citizen of the United States, residing at Bradley, in the county of Kankakee and 5 State of Illinois, have invented certain new and useful Improvements in Locks, of which the following is a specification.

My invention relates to improvements in locks, and it consists in the constructions, 10 combinations, and arrangements herein described and claimed.

An object of my invention is to provide a keyless lock including a casing with a slide- 15 able bolt which is held in its locked position by a spring pressed lug, a concealed plunger in the knob of the lock being provided to prevent the turning of the knob.

Another object of my invention is to provide a combination lock including a bolt 20 holding lug, and a plunger for preventing the knob from being turned, the lug and plunger being actuated as a combination to secure the freedom of the bolt.

Another object of the invention is to provide a lock of the character described, which 25 includes an ornamented casing having protuberances for disguising the button of the bolt lug.

Other objects and advantages will appear 30 from the following specification, reference being had to the accompanying drawings, in which:—

Figure 1 is a side elevation of a lock casing constructed in accordance with my in- 35 vention.

Fig. 2 is a side elevation of the part shown in Fig. 1, the cover of the casing being removed to show the bolt and the bolt locking lug.

Fig. 3 is a vertical section through the 40 device, and

Fig. 4 is a detail cross section through the knob showing the normally concealed plunger for holding the knob from rotation.

The lock casing consists essentially of the 45 base 1, and the cover 2 which is secured on the base 1 by suitable screws 3 as shown in Fig. 1. The cover 2 is ornamented as at 3, the ornamentation including a plurality of 50 protuberances 4 which are designed to disguise the push button 5 which is adapted to

serve as the depressor for a bolt locking lever 6.

The base 1 has a recess at 7 in which the bolt 8 is slideable, the cover 2 being located 55 on top of the bolt 8 and prevents loose play of the bolt in the casing in the manner clearly shown in Fig. 3. The bolt 8 is of a peculiar shape as shown in Fig. 2 wherein it will be observed there are two projectable 60 bolt members 9 which are adapted to project beyond the lock casing and engage a keeper. The bolt 8 also includes a cross bar 10 at the front and a bridge 11 which extends parallel to the bolt members 9. Spaces 12 are accordingly left by the formation of the parts of the bolt as shown in Fig. 2, and guide pieces 13 which may be integral with the base 1 of the lock casing extend up through the spaces 12 and serve as additional means 65 for guiding the bolt and keeping it from rattling in the casing.

A recess 14 at one edge of the bridge 11, receives one end of the lever 6, namely that end opposite the rounded plate 15 on which the push button 5 presses. The lever 6 is pressed inwardly by a leaf spring 16 when the bolt members 9 are projected from the casing. It is necessary to first push the button 5 when it is desired to retract the bolt 80 members 9 in opening the lock. In order to render the opening of the lock difficult for one without authority to open the lock, the exposed end of the push button 5 is disguised by making it appear as one of the 85 protuberances 4 of the ornamentation of the lock casing. It is therefore obvious that only a person acquainted with the combination or working of the lock, can select the correct one of the protuberances 4 to properly press on the button 5 and release the bolt 8.

It will be seen in Fig. 3 that the push button 5 has an enlarged base 5^a which is beveled at 5^b so that the angle which the 95 lever 6 makes in being depressed, may be readily followed by the push button.

It will also be observed that the base 1 is chambered at 6^a beneath the lever 6 to accommodate the depending end of the lug 100 when it is depressed by the push button 5.

The bolt 8 is retracted by turning a knob

17 which is covered by a casing 18 with a hole 19 normally out of registration with the end of a plunger 20. The plunger 20 works in a bore 21 in the shaft of the knob 17 as shown in Fig. 4.

5 The plunger 20 has a shoulder or collar 22 which is pressed against a shoulder which is formed between the bore 21 and a counter bore 23 by a spring 24. The spring 24 is held in place by a screw plug 25 at the bottom of the bore 21. The spring 24 forces the plunger 20 out of the aperture 19 when the casing 18 of the knob 17 is turned so as to bring the opening 19 into registration with the counter bore 23. The knob 17 has 10 bearing in the cover 2 of the lock casing and extends into a recess 27 as shown in Figs. 3 and 4. A collar 28 prevents the knob 17 from being pulled out and the collar 28 is placed in position on the end of the knob 20 shaft when the parts are assembled, in any suitable manner. A crank or wrist pin 29 is mounted eccentrically of the knob 17, and engages an opening 30 at the free end of a pivoted link 31. The link 31 is pivoted at 25 32 on the bolt 8 as shown in Fig. 2, and upon turning the knob 17 after the plunger 20 is released. The bolt members 9 may be retracted into the base 1 it being necessary however to first depress the lever 6 in order 30 that the bolt 8 may be freed at the recess 14.

The pivoted link 31 also has a hole 33 which is located directly beneath the plunger 20 when the parts are in the position shown in Fig. 4, and communicates with a cavity 34 in the adjacent portion of the bolt 8. The plunger 20 is adapted to be depressed through the hole 33 into the cavity 34 and held in place by the casing 18 of the knob 17. The knob 17 is thus prevented 35 from being turned in the manner which will be clearly understood from the drawing.

40 The operation of the device is as follows: The bolt members 9 are shown projected in Figs. 1 and 2. The casing 18 of the knob 17 has been turned so that the opening 19 is remote from the end of the plunger 20. The plunger 20 having previously been depressed through the opening 19, is held in 45 position by the solid portion of the casing 18. The other end of the plunger 20 is accordingly in position in the hole 33 and cavity 34, and since the wrist pin 29 is also in connection with the link 31, it follows 50 that the knob 17 may not be turned. It is only when a person acquainted with the combination of the lock, turns the casing 18 on the knob 17 bringing the opening 19 into registration with the end of the plunger 20, that the knob 17 is freed for turning. 55 It should be understood that the casing 18 is fixed on to the end 17 tightly enough to prevent turning of the casing when grasped casually by someone unauthorized to open 60 the lock.

When the casing 18 of the knob 17 is turned the required distance, the opening 19 will come into registration with the end of the plunger 20. The plunger 20 will then spring out of the opening 19 because of the 70 tension of the spring 24 behind it. The movement of the plunger 20 is sufficient to cause the inner end of the plunger 20 to clear the link 21 as shown in Fig. 4. The knob 17 may now be turned to act upon the bolt 75 8. The projection of the end 20 through the opening 19 of the casing 18 prevents further turning of the casing 18 when the knob is turned to retract the bolt 8.

80 The push button 5 is now depressed so as to rock the lever 6 on its fulcrum and cause the end of the lug to move out of the recess 14 to free the locking bolt 8. It will now be understood that by turning the knob 17, the wrist pin 29 will rock the link 21 and move the bolt 8 backwardly in the recess 7 in the base 1 of the lock casing.

85 The purpose of locating the plunger 20 which locks the knob 17 from rotation, beneath the casing 18, is that of concealment, and the purpose of locating the push button 5 in a place where it would be expected to find one of the ornamental protuberances 4, is that of disguise. It therefore follows that only a person authorized to open the lock will be acquainted with the details of the combination and be able to operate the parts correctly and effect the retraction of the bolt members 9 to open the lock.

90 While the construction and arrangement of the device is that of a generally preferred form, obviously, modifications may be made without departing from the spirit of the invention and scope of the claims.

95 I claim:—

1. A lock including a casing, a bolt slideable in the casing, a knob with a concealed plunger engaging the bolt and holding the knob from turning, a lever on the casing engaging the bolt, and a disguised button for moving the lever.

100 2. A lock including a casing having a bolt slideable therein, a knob having connection with the bolt and adapted to move the bolt by turning the knob, and a plunger in the knob adapted to engage the bolt to prevent the turning of the knob.

105 3. A lock including a casing having a bolt slideable therein, a knob having connection with the bolt and adapted to move the bolt by turning the knob, a plunger in the knob adapted to engage the bolt to prevent the turning of the knob, and a casing on the knob for concealing the end of the plunger and holding the plunger in engagement with the bolt.

110 4. A lock including a casing having a bolt slideable therein, a knob with a crank connection with the bolt for moving the bolt when the knob is turned, a plunger adapted to 115

120 125 130 open the lock.

- engage the bolt and prevent the turning of the knob, and a casing on the knob for holding the plunger in engagement with the bolt.
5. A lock including a casing having a bolt slidable therein, a knob with a crank connection with the bolt for moving the bolt when the knob is turned, a casing on the knob with an opening, a plunger in the knob held in engagement with the bolt by the casing to prevent the turning of the knob, and a spring on the plunger for moving the plunger out of engagement with the bolt when the opening in the casing is moved into registration with the end of the plunger. 70
6. A lock including a casing having a bolt slidable therein, a knob with a crank connection with the bolt for moving the bolt when the knob is turned, a casing on the knob with an opening, a plunger in the knob held in engagement with the bolt by the casing to prevent the turning of the knob, a spring on the plunger for moving the plunger out of engagement with the bolt when the opening in the casing is moved into registration with the end of the plunger, and means for limiting the movement of the plunger when actuated by the spring. 80
7. A lock including a casing with a cover having a recess, a knob having a shaft passing through the cover into the recess, and means on the end of the shaft of the knob engaging one wall of the recess for preventing the knob from pulling out. 85
8. A lock including a casing having a bolt slidable therein, a link pivoted to the bolt, a knob having a connection with the link whereby the bolt may be moved by the turning of the knob, and a plunger in the knob engaging the link for preventing the turning of the knob. 90
9. The combination of the bolt having a cavity, a link pivoted on the bolt with a hole adapted to register with the cavity, a knob having a crank connection with the link whereby the bolt may be moved upon turning the knob, and a plunger carried by the knob adapted to pass through the hole into the cavity to lock the parts together. 100
10. The combination of the bolt having a cavity, a link pivoted on the bolt with a hole adapted to register with the cavity, a knob having a crank connection with the link whereby the bolt may be moved upon turning the knob, a plunger carried by the knob adapted to pass through the hole into the cavity to lock the parts together, and a casing on the knob for holding the plunger in the hole and cavity. 110
11. A lock including a base having a filler with a chamber, a bolt slidable in the base with a bridge piece moving adjacent to the filler, the bridge piece having a recess, a lever stationed in the chamber adapted to enter the recess, a cover with a spring 65 pressing the lever into the recess, and a push button with a beveled edge engaging the lug, the beveled end being adapted to accommodate the change of angle of the lug when the button is depressed. 70
12. A lock including a base, a bolt reciprocal in said casing, a link pivotally connected to said bolt, a knob carried by said casing, a wrist pin carried by said knob and engaging said link, whereby when said knob is turned said link may swing or move for shifting said bolt, and means movably mounted off-center upon said knob releasably engaging said link for holding said knob against turning at certain times. 80
13. A lock including a casing, a bolt reciprocally mounted upon said casing, a link pivotally connected to said bolt, a knob rotatably supported upon said casing, a wrist pin carried by said knob and engaging said link, whereby when said knob is turned said link may be moved for shifting said bolt, a spring pressed plunger carried off-center of said knob releasably engaging said link, whereby said knob will be held from turning until said plunger is released from engagement with said link. 90
14. A lock including a casing, a bolt slidably mounted upon said casing, a link pivotally mounted upon said bolt, a knob rotatably supported by said casing, an eccentric pin carried by said knob and engaging said link, whereby when said knob is turned said link will be moved for shifting said bolt, a spring pressed plunger eccentrically mounted upon said knob and releasably engaging said link for holding said knob from turning at times, a rotatory casing fitting upon said knob, and said casing releasably engaging said plunger for holding the same in a releasable set position. 100
15. A lock including a casing, a bolt slidably upon said casing, a link pivotally connected to said bolt, a knob rotatably supported by said casing, a pin carried by said knob and engaging said link, a spring pressed plunger eccentrically mounted on said knob and releasably engaging said link whereby said knob may be held from turning at times, a casing fitting upon said knob, and conforming to the shape thereof, whereby said casing may be rotatably supported and at the same time held against displacement said casing releasably holding said plunger in a set position. 110
16. A lock including a casing, a bolt slidably upon said casing, a knob rotatably supported by said casing, a link pivotally connected to said bolt, a pin connected to said knob and engaging said link, said knob having an eccentrically formed bore communicating with a counter bore, a plunger extending through said bore, a collar carried 125

upon said plunger, a spring bearing upon said collar, a screw plug carried in the outer end of said bore, whereby said spring will be held in a set position, and means carried upon said knob for releasably retaining said plunger in engagement with said link.

Copies of this patent may be obtained for five cents each, by addressing the "Commissioner of Patents, Washington, D. C."

In testimony whereof I affix my signature in presence of two witnesses.

JOHN V. RITTMANIC.
